United States Patent Office.

ROBERT W. FISK, OF OLNEY, ILLINOIS.

Letters Patent No. 66,698, dated July 16, 1867.

IMPROVEMENT IN SAFETY-POCKETS.

The Schedule referred to in these Letters Patent and making part of the same.

TO ALL WHOM IT MAY CONCERN:

Be it known that I, ROBERT W. FISK, of Olney, Richland county, State of Illinois, have invented a new and useful Watch-Safety Pocket; and I do hereby declare the following to be a full, clear, and exact description of the nature, construction, and operation of the same, sufficient to enable one skilled in the art to which it appertains to construct and use the same, reference being had to the accompanying drawings, which are made part of this specification, and in which the same letters indicate similar parts.

Figure 1 is a rear view of the attaching plate.

Figure 2 is a vertical section.

A plate is attached to the back band of the pantaloons, or other garments, with a hook protruding through a button-hole into the pocket. Upon this hook the watch is hung, and secured thereon by a prong operated by a spring-lever pivoted to the plate. In the drawings—

A is the band of the pantaloons, to which the pocket B is attached. C is the front of the garment, and b the entrance to the pocket.—D is a plate, secured by notches in the strap E, and having a hook, e, which projects through a button-hole into the pocket B, so that the watch F may hang thereon. When the watch is hung in position in the pocket upon the hook e, the prong m is made to close the opening, so that the watch cannot be unhooked. The upper edge of the plate D is rounded, so as to hold a pin, n, around which the wire M is coiled, one end forming the prong m, which projects through the button-hole and comes in contact with the hook e, the other end, m', forming a means of fastening the prong m against the hook e, when the end m' is secured in the catch p like a brooch-pin. The pin n is fastened in its socket, and one end, S, being prolonged and bent around under the wire, forms a spring to elevate the said wire when freed from the catch p.

The device is a safeguard against the watch being picked from the pocket, as it cannot be detached from the hook until the prong m is detached from the hook e, by releasing the pin m' from the catch p. The device is shown as attached to the waist of a pair of pantaloons, but it is equally applicable to other garments.

Having described my invention, what I claim therein as new, and desire to secure by Letters Patent, is—

A watch-safe, consisting essentially of the plate D, hook e, prong m and m', when combined and arranged to operate in the manner and for the purpose specified.

To the above specification of my invention I have set my hand this day of

ROBERT W. FISK.
